UNITED STATES PATENT OFFICE.

FERDINAND SCHNEIDER, OF FULDA, GERMANY.

SYSTEM OF ELECTRIC CONTROL.

Application filed June 5, 1924. Serial No. 718,156.

To all whom it may concern:

Be it known that I, FERDINAND SCHNEIDER, a citizen of Germany, residing at Fulda, Germany, have invented certain new and useful Improvements in Systems of Electric Control, of which the following is a specification.

My invention relates to apparatus for regulating clocks, and more particularly to systems in which a master clock is regulated by electric impulses at predetermined intervals, say of one minute, and regulates a plurality of secondary clocks.

Heretofore, in systems of the kind described, the receiver, for instance a coherer, was supplied with current during the intervals of the impulses, in order to prevent disturbance of the apparatus by foreign waves. This expedient, however, is not satisfactory on account of the high current consumption involved, and decohering is difficult, particularly if the coherer has been influenced by strong waves.

Exact decohering is only possible if the force of the electromagnet operating the tapper is constant, a condition which cannot always be fulfilled, as the energy of the battery supplying said electromagnet decreases.

The operation of decohering requires the actuation of auxiliary contacts for breaking the coherer circuit when the coherer is tapped.

As the relay or electromagnets of the master clock are permanently in the coherer circuit, the coils of the electromagnets must have high ohmic resistance in order to reduce current consumption. This, however, involves the drawbacks that only a very small amount of power is available for moving on the clockwork and the like, and only very delicate contacts can be fitted, that the operation of the contacts is difficult on account of their low contact pressure, so that only a limited number of secondary clocks can be regulated by a master clock through the agency of relays or mercury contacts, and that contact sparks will cause undesirable excitation of the coherer.

In my improved apparatus I overcome

these drawbacks by rendering the coherer of a master clock immune to foreign waves notwithstanding the fact that it is not permanently under current, as in the prior systems. This is effected by a switch actuated by the 55 clockwork which causes the circuit of the coherer to be ready only at the periods of impulse. The only load on the coherer circuit which is completed by the impulse, is the release of the escapement wheel which 60 is effected without relay.

In case that the impulse should fail to arrive, the switch will close an auxiliary circuit in parallel to the coherer which keeps the clockwork going and causes the other 65 operations to be performed notwithstanding the fact that the coherer has not been cohered.

The switch is actuated and the spring of the clockwork wound up by means of an 70 electromotor which is switched on by the clockwork at predetermined intervals, say one minute, but disconnected by the train of wheels for the switch which the motor had started going. This train also controls commutating contacts for the secondary clocks, 75 the contact pressure being so considerable that intermediate relays may be dispensed with and nevertheless a considerable number of secondary clocks be regulated by one 80 main clock.

To keep local disturbances away from the coherer, the contact sparks of the commutators for the secondary clock circuits are extinguished by an ionisator which may be 85 a coherer resistance with flake filling. Similar ionisators are provided for extinguishing the commutator sparks of the electromotor and the switching sparks of the coherer circuit.

Decohering is effected by a mechanically actuated tapper. This removes the disturbances by local electric waves in an electromagnetic tapper, auxiliary springs for breaking the circuit during tapping are dispensed with, the intensity of the tapper blow is uniform and adjustable. Instead of an electromotor, I may provide weights or springs.

In the drawings affixed to this specifica- 100

tion and forming part thereof an apparatus embodying my invention is illustrated diagrammatically by way of example.

In the drawings—

5 Fig. 1 is an elevation of a master clock,

Fig. 2 is a detail view illustrating the operation of the tapper,

10 Figs. 3 and 4 are detail views of the switch controlling the electromotor and coherer circuits,

Fig. 5 is a detail view illustrating the means for locking the switch controlling the circuit of the electromotor,

15 Fig. 6 is an elevation illustrating the commutating contact and extinguishing means of a secondary clock circuit.

Fig. 7 is an end elevation of the commutating cam and parts connected therewith,

20 Figs. 8 and 9 are detail views illustrating the release of the escapement wheel for a master clock operated by weights or springs.

The base 1 carries the conducting frame-plate 2 of the clockwork, in which is placed the minute wheel 3, on the axle 6 of which 25 the barrel-wheel 4 together with the main spring 5 is mounted. With the minute wheel 3 engages the pinion 9 of the wheel 7, to the axle of which is fastened the detent disc 8. With the wheel 7 the pinion 11 of the 30 balance wheel 10 meshes, the escapement 12 of the escapement wheel 13 cooperating with said balance wheel. 14 is the spiral spring of the escapement wheel. An intermediate wheel 15 engages on one side with the barrel-wheel 4 and on the other side with a wheel 16, which is on the same axle as a pin-wheel 17. The wheel 17 provided with the catches 18 engages with the pinion of the wheel 19, on the axle of which is set the 35 switch disc 20 with cams 21 together with a switch lever 22. The switch disc wheel 19 engages with the pinion 25 of the wheel 24 and the latter with the pinion 27, on the axle of which is fastened the belt-pulley 26. 40 The latter is rotated through the belt 28 by the disc 29 set on the axle of the electro-motor 30. One brush of the motor 30 is connected by a conductor 31 with a battery 34, whilst the other brush is connected through 45 the conductor 32 by means of screws 33 with the frame plate 2. From the battery 34 a conductor 35 leads to a contact pin 37 insulated by the insulating sleeve 36 against the frame 2. Beneath this contact pin the rotary 50 shaft 38 of the contact angle lever 39 is mounted on the frame 2. A spring (not shown) tends to force this lever against the contact pin 37 when the catch 41 pivoted in the frame releases it. The arm 42 of the 55 catch 41 is under the pressure of a spring 44. In the frame 2 is also mounted the shaft 45 of the drop-hammer 43—46 releasing the catch 41—42. The stop pins 47 limit the 60 movements of the catch 41—42. There is also mounted in the frame 2 the release catch 65

48 of the electromagnet armature 52 moved by the switch disc 20 by means of the pin 23, which catch is under the pressure of a spring 50 and its movement is limited by the stop pin 49. On the frame 2 is also 70 mounted the shaft 55 which carries the two-armed lever 51—52 of which the arm 52 is an armature of soft iron and has on its curved outer surface an extension 53 shaped as a plate-spring. There is further fastened 75 to the frame 2 a stop screw 54 limiting the movement of the armature 52, and an electromagnet 56—57 whose coil on the one hand is connected by the conductor 58 with the rear coherer upright which is concealed 80 in Fig. 1 by the front coherer upright 64, and on the other hand by the conductor 59 with a contact spring 91 inserted in the frame 2 and insulated by the insulating sleeve 96. To the conductor 58 is fitted the conductor 61 which leads to the contact spring 93 insulated by the insulating sleeve 94 against the frame 2. A further conductor 60 leads on one side to the contact spring 92 insulated by the insulating sleeve 95 against 85 the frame 2 and on the other side in its extension 62 to the front upright 64 on the base 1. The coherer support itself consists of two uprights, the U-shaped holders 67 and the screws 68 and 69 carrying the coherer 90 66. The coherer upright 64 is connected by means of the screws 63 through the conductor 70 with one pole of a battery 71, the other pole of which is conductively connected by the conductor 72 and a screw 73 with the frame 2. In the latter is carried a pinion 89 engaging with the pin-wheel 17, on the axle of which is secured a cam 90. The accessory contact members 85, 86 and 87 are fastened to the insulating member 88 rigidly 95 connected with the frameplate 2. The contact member 87 is connected by the conductor 78 with the minus pole of the battery 79, from the plus pole of which the conductor 80 leads to the frameplate 2 and is held thereto by means of the screw 81. The contact spring 85 is fitted to one system conductor 82 of the secondary clocks 84, whilst the contact spring 86 is connected with the second system conductor. 100

The operation of my improved master clock is as follows:—The minute wheel 3 is rotated by the spring 5 in the direction followed by the hands of a clock, because the spring 5 with the inner end hooked onto the shaft 6 transmits its tractive effort to the minute wheel. The outer end of the spring 5 is hooked with the loosely mounted spring wheel 4 and the latter is held in its position by its engagement with the wheel 15. The action of the minute wheel 3 is transmitted in the usual manner to the other known parts 7, 9, 10, 11, 12, 13 and 14 by which the escapement wheel 13 is set rocking. As the minute wheel 3 has 480 teeth and there are 105 110 115 120 125 130

eight pins on the pinion 9, the wheel 7 performs one revolution per minute. Consequently, the disc 8 raises the drop hammer 45, 46, 48 until it drops into a notch of the disc 8 and with its weight 48 moves the arm 42 of the catch 41 downwards, until the catch arm 42 engages its stop-pin 47 (Fig. 1). The hereby released contact lever 40 starts upwards under the action of the spring 10 coiled on its member 38, makes contact with the contact pin 37 with its contact-spring arm 39 and thereby closes the electromotor circuit 38, 39, 37, 35, 34, 31, 30, 32, 33. The electromotor 30 rotates by means of the discs 26—29 and the belt 28, the pinion 27, the wheel 24, with pinion 25, the switch-disc wheel 19 and the pin wheel 17, of which the wheel 16 rotates the intermediate wheel 15 and therewith the barrel-wheel 4, by which the spring 5 is rewound. During the rotation of these elements various operations occur. In the first place, the clockwise rotating pin wheel 17 by means of its catches 18 completes the downward movement of the tapper 74—75, of which the short arm 77 finally slides off from the said catch 18 under the pull of the spring coiled on the shaft 76, whereupon the tapper 74 springs upwards and strikes the coherer 66 (Fig. 2). Although the latter is without current at the time it requires tapping, in order to arrest any sintering of the coherer mass, shortly before the arrival of the electric impulse from the master clock.

The next stage of operation is accomplished by the switch-wheel 19, which during its anti-clockwise rotation lifts the shorter arm of the catch 48 by means of the pin 23 on the rim of the wheel, whereby its longer arm, hitherto engaging the stop-pin 49 under the pressure of the spring 50, is moved downwards until the short arm 51 of the armature 52 slides away from the catch body and the latter falls downwards by its own weight under rotation about the axle 55. The spring 53 engages the rim of the escapement wheel 18 and finally arrests the wheel, stopping the clockwork, while the switch disc wheel 19 continues its rotation. The switch disc 20 fixed on the axle of the wheel 19 engages with its front end the contact spring 91 set in the insulation sleeve 96, whereby the coherer circuit is switched on, although the coherer is not yet cohered. The circular front end of the switch disc 20 then slides under the contact pressure of the spring 91 further (Fig. 3) and at the next moment the coherer 66 is cohered by the impulse sent from the master clock, thereby closing the circuit so that now the coherer circuit 20, 91, 59, 56, 58, 65, 66, 69, 68, 67, 64, 63, 70, 71, 72, 73 is closed, the pole 57 of the electromagnet 56 becomes energized and the armature 52 is attracted. Meanwhile, the spring 53 starts its sliding move-

ment forward, away from the escapement wheel 18, and thereby sets the works going again. During the proceeding, the short arm 51 of the armature 52 has slid over the nose of the catch 48 into its initial locked position. At the next stage, on further rotation of the switch disc 20, its cam 21 closes the remaining contacts 92, 93, positively and at considerable pressure, whereby the auxiliary circuits 20, 91, 92, 60, 62, 63, 65, 61, 93 parallel to the coherer are closed. This last operation is a safety switching which serves to keep the clock going, even if for any reason the electric impulse should fail to arrive from the central.

On further rotation of the switch disc 20, the contact spring 91 slides away from the cam 21, whereby the contacts 91, 92 and 93 of the coherer circuit, and of the auxiliary circuit are separated, the coherer 66 is without current, and, as the circuits are completely interrupted, the coherer even if it is merely accidentally influenced by foreign waves, cannot disturb the regulated working of the clockwork. After the switching off of the electromagnet 56—57, the armature 52 remains in its idle position (Fig. 1) until the same performance is repeated in the next minute.

Shortly before the revolution of the switch disc wheel 19 is completed, the arm 22 mounted on the same shaft with this wheel and rotating with it, engages the nose 40 of the contact lever 38, 39 (Fig. 5), whereby the latter is placed in its idle position and locked by the catch 41.

The reaction of the catch spring 44 is so regulated that the catch arm 42 raises the hammer 43 resting on it to the end of its stroke. Meanwhile, the contact 37, 39, and therewith the circuit of the electromotor 30 is interrupted, whereupon the vertical tread and switch wheels also end their rotation. For stopping the wheels no special apparatus is provided, because the idle running of the motor 30 as well as the switch wheels is counteracted by two springs, the draw-spring 5 of the clockwork together with the spring of the tapper 75—77. The pitch of the two wheels 17, 19 is so chosen, that at the completion of a revolution of the wheel 19 the tapper lever arm 77 is raised by the tension of the tapped spring until shortly before its falling away from the respective catch 18. Further, during one revolution of the switch disc wheel 19, the wheels and pinions 16, 17, 15, 4 are so rotated together, that the spring 5 is rewound for one minute and that the spring-wheel 89 engaging with the pin wheel 17 makes a half-revolution, during which the cam 90 for instance slips past the contact spring 85, whereby the secondary clock circuit 90, 85, 82, 84, 83, 87, 78, 79, 80, 81 is closed, which causes the hands of the secondary clocks to move on.

At the next half revolution of the cam 90, it slips past the contact spring 86 and thereby connects the system for reverse flow of current. In both cases, the switching operations are effected under high contact pressure, because the cam 90 is operated by the high speed motor 30 at great reduction, so that it is able to control the heavily loaded switch members without difficulty. Consequently, the switch parts are able to carry high current intensities, so that a great number of secondary clocks can be connected with the system.

In the operation described, time is indicated by a dial-train (not shown) actuated by the minute wheel 3, but the intermittent reception of the electric wave which the master clock sends each minute may also be utilized for indication, either by indicating the raising of the armature 52, or by causing the armature 52 to directly actuate the dial-train.

From the description of operation, it will appear that my improved master clock cannot be disturbed by foreign waves, because the switch members 20—91 serving to receive the wave sent are ready for receiving the impulse only at the normal time of arrival of the impulse, with a small plus and minus tolerance.

In order to avoid the disturbing influence of the contact sparks of the alternate current contact of the secondary clocks on the reception coherer, the latter is constructed as illustrated in Figs. 6 and 7. The devices at present provided do not fulfill their object satisfactorily, because the means of extinguishing the sparks, such as condensers, resistances and the like, must stand in a quite definite relation to the working energy as well as to the electromagnet coils switched into the secondary clock circuit. In practice, however, this condition is difficult to fulfill, as, on the one hand, the energy of the battery is not constant, and, on the other hand, secondary clocks may be displaced or their number increased, causing alterations in the arrival of the extra current. Consequently, contacts with unreliable spark extinguishing means are not suited for master clocks regulated by electric waves, because the sparks, which are only apparently repressed, will generate more electric waves and thereby excite the reception coherer of the master clock at odd times and so disturb it. A further disadvantage of the known extinguishing devices is the use of auxiliary contacts with insufficient pressure which become soiled and oxidated, so that the sparks are not effectively extinguished.

In the commutator of the present invention, this drawback is removed by switching into the sparking gap a coherer resistance with flake filling of known type which adapts itself automatically to the varia-

tions of the battery and also automatically alters its resistance with resistance variations in the system. The spark extinguishing action is perfect, so that the commutator contact with leaf coherer resistance can without difficulty be used, even with main clocks regulated by electric waves, without disturbing the reception coherer. Finally, in the commutator according to the invention, not only the main but also the second contacts are positively operated sliding contacts, which have the advantage of keeping themselves bright by constant friction, so that therewith a reliable contact is effected. As the elimination of the extra current sparks is quite successfully accomplished, the contact surfaces do not require a layer of platinum, which is an important feature, from the technical and economical point of view.

The disc 105 (Fig. 6) of the cam 90 is fixed on a shaft 119 operated by the clock-work, but insulated from it by a sleeve 97. There is further set on the insulating sleeve 97 the disc 89, in which switch pins 99, 100 are set to either side of the cam 90. A further switch pin 98 is inserted in the cam 90, whilst the current conveying spring 104 engages under pressure on the back of the cam disc 105. To the frame 2 of the clock-work is secured the insulation member 88 and in its centre the contact member 87 is fixed by means of screws, the screw 120 being connected with one pole of the battery 79 by the conductor 78, while the other pole of the battery 79 is connected with the base 21 of the spring 104 by the conductor 80. To both sides of the insulating member 88 are screwed laminated contact springs 85, 86. Beneath the cam 90 the insulating member 103 is fitted to the wheel-work frame 2 and to its sides are secured two auxiliary contact springs 101, 102 by means of screws. The contact spring 101 is connected with a flake coherer resistance 107 by the conductor 106, and said resistance 107 is connected by the conductor 108 with the contact spring 85 by means of a screw 122. The other auxiliary contact spring 102 is connected with another flake coherer resistance 110 by the conductor 109, and said resistance 110 is connected by the conductor 111 with the main contact spring 86 by means of a screw 123. To the main contact springs 85, 86 are connected conductors 83, 82 which terminate at the binding posts of the secondary clocks 84.

The operation of this switch device is as follows: By the main clock, the switch disc 89 and the cam disc 105, are rotated clockwise through 180°, for instance, every minute. In the first place, the pin 99 mounted on the insulated disc 89 engages the main contact spring 85 and therewith breaks the contact 85—87, then the pin

- 98 on the cam 90 engages the auxiliary spring 101, whereby the coherer resistance circuit 79, 80, 121, 104, 98, 101, 106, 107, 108, 122, 83, 84, 82, 123, 86, 87, 120, 78 is closed. The hand of the auxiliary clock 84, however, does not yet move for want of current. On continued rotation of the switch member, the cam 90 engages the main contact spring 85, at the same time 5 the pin 99 releases the spring 85, whereby the secondary clock circuit 79, 80, 121, 104, 90, 85, 122, 83, 84, 82, 123, 86, 87, 120, 78, is closed for full intensity, whereupon the hand of the secondary clock 84 is moved on 10 for the space of one minute. On further rotation, the cam 90 releases the spring 85 which is then actuated by the pin 100 mounted on the disc 89, whereby the circuit 79, 80, 121, 104, 90, 85, 122, 83, 84, 82, 123, 86, 87, 120, 78 is apparently opened. However, this is not yet the case, because the coherer circuit which at the same time is 15 still impressed, prevents complete breaking, until the pin 98 releases the auxiliary contact spring 101 and therewith opens the last-named circuit, without any formation of sparks. Hereupon, the pin 100 releases the spring 85 and the latter returns under pressure to its normal position on the contact member 87. At the same time, the 20 clockwork stops. At the next start, the pin 99 mounted on the disc 89 engages the main contact spring 86 and opens the contact 86—87, then the pin 98 engages the auxiliary contact spring 102, then the cam 90 engages the spring 86. At the same time, the pin 99 releases the spring 86, then the tappet 90 releases the spring 86 and the pin 100 exerts pressure against the spring 86, then the pin 98 releases the spring 102, then the pin 100 releases the spring 86 and the latter returns to its normal position on the contact member 87; at the same time, 25 the clockwork stops. This second operation is completed in the same manner and with the same effect as the first operation. The current, however, flows in opposite direction to that of the first operation, so that the hands of the secondary clock are moved on 30 for the space of another minute.
- As will appear from the description of the two operations, the making and breaking of the circuits are started and terminated by the coherer resistance which is switched in before and after, so that the extra currents in both cases are absorbed by the flake coherer. The contact sparks are completely extinguished, so that even 35 wave indicators will not indicate them.
- Similar coherer resistances with flake filling can of course also be employed in the master apparatus or clock to extinguish the collector sparks of the electromotor 30 and the sparks at the contacts 37, 39 (Fig. 1).
- With the master clock can also be used,
- instead of the electromotor 30, a weight or spring traction work for maintaining the working, as well as for the rotation of the switch disc 20. With such driving means it is essential that the release and stoppage 40 of the clockwork should be effected suddenly and at regular intervals, so that the switch disc 20 rotated with the wheel-work ensures the reliable preparation of the reception coherer 66 for receiving the waves. 45 In the regulating device according to the invention this result is obtained in the simplest manner by the use of a lever having several arms (Figs. 1, 8 and 9), without increasing the load on the clockwork.
- The wheels and pinions 19, 24, 25, 26 and 27 mesh with the known gears and pinions of a weight or spring drive. The clockwork is released for rotation by the hammer 43 which is operated by the clockwork every minute. In the state of rest (Fig. 8) a lever arm 116 projecting from the disc 113 lies on the circumference of the disc 26 formed as a fly-wheel and arrests the disc by friction, whilst a second 50 lever arm 114 of the small disc 113 has engaged a tongue in the notch 118 of the disc 117 mounted rigidly on the switch disc wheel 19, whilst the circularly curved end 115 of the lever arm 114 approaches the switch lever 39, but does not touch it. The little disc 113 rocks about a pin under the weight of its arms 114, 115, and 116. At 55 every operation of the hammer 43, the lever 39 (Fig. 9) released by the catch 41 moves upwards under spring pressure and raises the arms 114, 115. At the same time, the brake-arm 116 also moves away from the flying wheel disc 26, whereby the clockwork is released for rotation. The latter, 60 19, 22, 117, 24, 25, 26, 27 now rotates until the arm 22 brings the lever 39 back to its locked position and subsequently the tongue of the lever arm 114 engages the notch 118 of the disc 117, whereby the brake 65 lever 116 again engages and arrests wheel disc 26. On the shaft of the switch disc wheel 19 is mounted the switch disc 20, 21 (not shown in these figures) which prepares the parts for the reception of the waves, as 70 described. The spirit of the invention is not departed from by using the levers 114, 115 and 116 for stopping and releasing the electromotor disc 26 or 29, nor by using the catch-members operated by the falling hammer 43 together with release levers in clockworks operating for instance master clocks without wave regulation.
- I wish it to be understood that I do not desire to be limited to the exact details of 75 construction shown and described, for obvious modifications will occur to a person skilled in the art.
- I claim:—
1. In an apparatus of the kind described 80

- in combination, a master clock comprising a clockwork and means for automatically and periodically rewinding said clock-work, an electric circuit including a make and break contact and an electromagnet, the armature of which is attracted when said circuit is closed, locking means holding said armature in its attracted position and adapted to periodically release it, regulating means controlled by said clockwork and adapted to alternately bring said locking means into its locking and releasing positions, said armature when released engaging and arresting the escapement wheel of said clockwork, and when attracted imparting to said escapement wheel an initial swinging movement, said regulating means operating also said make and break contact, a receiver for electric wave impulses in the circuit of said electromagnet and adapted to be prepared for the reception of an impulse by closing said contact just before the impulse arrives to complete said circuit when the impulse does arrive, secondary clocks connected by electric circuits with said master clock, contacts in said connecting circuits and means operated by said clockwork for alternately closing and opening said contacts in said connecting circuits.
2. In apparatus of the kind described in combination, a master clock comprising a clockwork and means for automatically and periodically rewinding said clockwork, an electric circuit including a make and break contact and an electromagnet, the armature of which is attracted when said circuit is closed, locking means holding said armature in its attracted position and adapted to periodically release it for arresting said clockwork, regulating means controlled by said clockwork and adapted to alternately bring said locking means into its locking and releasing positions, said regulating means operating also said make and break contact, a receiver for electric wave impulses in the circuit of said electromagnet for completing it when the impulse arrives, said receiver having a secondary circuit with a contact actuated by said regulating means for short circuiting said receiver as a reserve in case an impulse should not arrive, secondary clocks connected by electric circuits with said master clock, contacts in said connecting circuits and means operated by said clockwork for alternately closing and opening said contacts in said connecting circuits.
3. In apparatus of the kind described in combination, a master clock comprising a clockwork, an electromotor for automatically and periodically rewinding said clock-work, an electric circuit for said electromotor including a make and break contact, an electric circuit including a make and break contact and an electromagnet, the armature of which is attracted by closing said electromagnet circuit, locking means holding said armature in its attracted position and adapted to periodically release it for arresting said clockwork, regulating means controlled by said clockwork and adapted to alternately bring said locking means into its locking and releasing positions, said regulating means operating also said make and break contacts in the electromotor and electromagnet circuits, a receiver for electric wave impulses in said electromagnet circuit for completing it when the impulse arrives, said receiver having a secondary circuit with a contact actuated by said regulating means for short circuiting said receiver as a reserve in case an impulse should not arrive, secondary clocks connected by electric circuits with said master clock, contacts in said connecting circuits and a cam actuated by said clockwork at a high rate for alternately closing and opening said contacts in said connecting circuits.
4. In apparatus of the kind described in combination, a master clock comprising, a clockwork and means for automatically and periodically rewinding said clockwork, a brake adapted to automatically and periodically arrest said clockwork, means controlled by said clockwork to bring said brake into its operative position and out of it, an electric circuit including a make and break contact and an electromagnet the armature of which, when attracted, imparts to said clockwork an initial movement, locking means controlled by said clockwork for holding said armature in its attracted position and for releasing it, regulating means controlled by said clockwork operating said make and break contact, an impulse receiver inserted in said electromagnet circuit for completing it when the impulse arrives, said receiver having a secondary circuit with a contact actuated by said regulating means for short circuiting said receiver, secondary clocks connected by electric circuits with said master clock, contacts in said connecting circuits and a cam actuated by said clockwork for alternately closing and opening said contacts in said connecting circuits.
5. In apparatus of the kind described in combination, a master clock comprising a clockwork, means for automatically and periodically rewinding and arresting said clockwork, an electric circuit including a make and break contact and an electromagnet, a locking means for periodically locking and releasing the armature of said electromagnet in its attracted position, regulating means controlled by said clockwork to operate said locking means and said make and break contact for preparing said electromagnet circuit, an impulse receiver in said electromagnet circuit for completing it when the impulse arrives, said receiver hav-

ing a secondary circuit with a contact actuated by said regulating means for short circuiting said receiver, secondary clocks connected by electric circuits with said master clock, main contacts in said connecting circuits, secondary circuits including secondary contacts and resistance coherers with flake filling, and a cam actuated by said clock-work for alternately closing and opening said main contacts and said secondary contacts.

In testimony whereof I affix my signature.
